UNITED STATES PATENT OFFICE.

SIMEON S. JACKSON, OF BOSTON, MASSACHUSETTS, ASSIGNOR TO THE STAFFORD COMPANY, OF READVILLE, BOSTON, MASSACHUSETTS, A CORPORATION OF NEW JERSEY.

LOOM.

1,200,500.

Specification of Letters Patent. Patented Oct. 10, 1916.

Application filed August 28, 1912. Serial No. 717,444.

To all whom it may concern:

Be it known that I, SIMEON S. JACKSON, a subject of Great Britain, residing at Readville, Boston, in the county of Suffolk, State 5 of Massachusetts, have invented a certain new and useful Improvement in Looms, of which the following is a specification, reference being had therein to the accompanying drawings.

10 The invention relates to looms of the class in which replenishment or change of weft or filling is effected automatically by introducing into a shuttle on the lay of a loom a bobbin or other carrier loaded with 15 weft or filling, and expelling from such shuttle the weft-carrier previously contained therein.

The invention comprises novel means for 20 delivering loaded weft-carriers successively from the hopper or magazine therefor to the means for transferring the same. Also, transferring devices comprising means by which a loaded weft-carrier supplied by the said hopper or magazine is moved into position adjacent a shuttle on the lay of a loom, and means by which the said weft-carrier is introduced into the said shuttle to take 25 the place of the weft-carrier previously contained therein. In the preferred embodiment 30 of the invention the latter means, or transerrer proper, is mounted upon the lay. Also, a chute for the expelled weft-carrier having operative connection with the said means for moving the loaded weft-carrier whereby, when such means is moved 35 to present the loaded weft-carrier in readiness to be introduced into the shuttle, the said chute also is moved into a working position to receive the expelled weft-carrier, 40 and when the said means is returned to its normal position the chute also is retracted out of the way of the working parts in connection with the lay. Also, the combination 45 of the said transferring devices with a change-shaft by means of which such parts are actuated. Also, the combination with the transferring devices embracing the different means aforesaid, and the change-shaft, of means for suspending the operation 50 of the weaving instrumentalities for the performance of the change-operations and subsequently automatically causing such

instrumentalities to resume operation, and various novel combinations of parts.

An embodiment of the invention is shown 55 in the drawings, in which latter—

Figure 1 is a side elevation of portions of a loom at the replenishing side thereof, with the said embodiment applied thereto. Fig. 2 is a side elevation of the driving side of 60 such loom. Fig. 3 is a front elevation of the parts at that side of the loom which is represented in Fig. 1. Fig. 4 is a front elevation of the parts at that side which is represented in Fig. 2. Fig. 5 is a view 65 on an enlarged scale showing in side elevation the hopper or magazine and the carrier for taking a loaded weft-carrier rearward toward the lay. Fig. 6 shows the parts of Fig. 5 in front elevation. Fig. 7 70 is a top view thereof. Fig. 8 is a sectional view of portions thereof. Fig. 9 shows in side elevation portions of the lay, the transerrer or pusher, and the shuttle-positioning devices. Fig. 10 shows in front elevation the parts of Fig. 9, with the addition of the actuating lever, cam, and a portion of the change-shaft. Fig. 11 is a plan view of the parts of Fig. 9. Fig. 12 is a side elevation of the lever, cam, etc., shown in the 75 lower part of Fig. 10. Figs. 13, 14, and 15 are respectively a side elevation, front elevation, and plan view of certain of the parts for actuating the change-shaft and controlling the actuation thereof. 80

The drawings show a construction and arrangement providing for inserting the fresh weft-carrier downward into the open top of the shuttle and expelling the previous weft-carrier downward through the open 90 bottom of the shuttle and an opening in the lay beam. Such is the preferred construction and arrangement, but the invention is not necessarily restricted in all instances to 95 downward insertion and expulsion.

Having reference to the drawings, 1 is the loom-frame, the breast-beam being marked 2 in Figs. 3, 4, 6, and 7.

At 3, 3, Figs. 1 and 2, are the lay-swords, 4, 4, being the lay pitmen, and 5 being the 100 crank-shaft. 6 is the lay-beam. 7 is the front-plate of the shuttle-box on the end of the lay at the replenishing side of the loom, 8 (Figs. 1 and 9) the shuttle-box back, 9

(Figs. 1 and 9) the binder, and 10 the top-plate of the shuttle-box.

11, Figs. 1 and 3, is one of the picker-sticks, and 12 is the picker-mounted thereon.

5 These are all ordinary parts of a loom.

13, Figs. 9, 10 and 11, is a shuttle occupying the shuttle-box, it being a self-threading shuttle of the usual character employed in looms of the class aforesaid.

10 A hopper or magazine for loaded weft-carriers is shown at 14, Figs. 1, 3, and 5 to 8. Shuttle-bobbins 15, 15, filled with weft or filling are shown therein. The said hopper or magazine has combined therewith 15 means for delivering the weft-carriers successively to the transferring carrier. Such means will presently be described.

Referring to the transferring devices, 16, Figs. 1, 3, and 5 to 8, is a carrier. It is constructed to receive a loaded weft-carrier from the hopper or magazine, and has combined therewith means for moving it rearward toward the lay, to present such weft-carrier to the action of the device which introduces the weft-carrier into the shuttle, and for subsequently moving it forward to receive the next weft-carrier from the hopper or magazine.

17, Figs. 1, 9, 10 and 11, is a device for transferring the weft-carrier from the carrier to the shuttle. It has combined with it means for moving it to push the weft-carrier held by the carrier from the latter into the shuttle occupying the shuttle-box, and then

35 retracting the transerrer from the shuttle.

18, Figs. 1 and 3, is a chute by which the weft-carrier just expelled from the shuttle is deflected into a receiving-box 19 therefor.

40 The said chute normally occupies an idle forward position, as in Fig. 1, out of the way of the picker-stick and other parts in connection with the lay. It is caused to move rearward at the same time that the carrier does, and to assume a position to receive upon its 45 surface the weft-carrier that is expelled from the shuttle, afterward moving forward simultaneously with the carrier and remaining in its idle position until the carrier is again moved rearward to the lay.

50 20, Figs. 9, 10, and 11 is a shuttle-positioning arm. The said arm occupies normally an upraised position above the path of the moving shuttle, as in said figures, and when called into action is caused to swing

55 downward and outward in a vertical or substantially vertical plane so that if the shuttle, after coming to rest, should occupy a position misplaced toward the middle of the loom the arm will engage with the inner end of the shuttle, and move the latter outward within the shuttle-box into the position required to enable it to receive the weft-carrier that is pushed into the shuttle-cavity by the action of the pusher. After having positioned the shuttle, the arm 20 rises into

its normal position above the path of the shuttle.

So far as the carrier 16, transerrer 17, chute 18, and shuttle - positioner 20, more broadly considered, are concerned, the precise mechanical arrangements for actuating the same are not material; nor are the manner and means of determining the time of action thereof.

Having regard to the more specific phases 75 of the invention, on the other hand, the invention includes among its features the combination of the said devices with a change-shaft whereby they are operatively controlled. The change-shaft is shown at 210. 80 The manner and means whereby in this embodiment of the invention the said devices are operatively combined with the change-shaft will presently be described. The change-shaft normally does not rotate, but 85 at the required time is called into action by either weft-detecting or pattern-devices and thereupon through its rotation and its control of the devices aforesaid brings about the change of weft-carriers in the shuttle. 90 Preferably, the invention is employed in a loom in which the action of the weaving instrumentalities is arrested automatically for the change, the change-shaft being called into action, and when the change has been 95 effectuated the weaving instrumentalities are restarted and the change-shaft ceases its rotation. A loom on this order, but changing shuttles instead of changing weft-carriers in a shuttle on the lay, is shown and described 100 in my prior Patent No. 945,722, dated Jan. 4, 1910.

Referring more in detail to the construction illustrated in the drawings, the hopper or magazine 14, Figs. 1, 3, and 5 to 8, is of the upright hopper-type, it having side-guides 14^a, 14^b, for the heads and tips of the weft-carriers 15. For its support, it is furnished with ears 14^b, 14^b, Fig. 3, fitting upon a horizontal rod 14^c, the inner end of which occupies a socket 14^d in the upper portion of a two-part stand 14^e rising from the loom-frame at the end of the breast-beam 2, the 110 said end of the rod being secured in said socket by clamp-screws 14^f, 14^f. The position of the hopper or magazine laterally upon the supporting-rod is adjustably determined by means of a collar 14^g, and a hub 14^h, which are fixed by clamp-screws 14ⁱ, 14ⁱ, upon the rod 14^c at opposite sides of one of the ears 14^b. To enable the hopper or magazine to yield so as to obviate breakage in case forwardly-acting pressure should be exerted against the lower portion thereof, as in case the carrier 16 in its forward movement should encounter a weft-carrier on the shelf 29 at the bottom of the hopper, the ears 14^b, 14^b, are capable of turning upon the rod 14^c. The hopper or magazine is held normally in the working position represent- 115 120 125

ed in the drawings by means of a contracting spiral spring 14^c, having one end thereof engaged with the upper portion of the hopper or magazine and its lower end engaged with an arm 14^m forming part of hub 14^c. This spring holds an upper portion of the hopper normally in contact with arm 14^m. It will yield to permit the lower portion of the hopper or magazine to swing forward when forwardly-acting force is exerted against such portion, and afterward will return the hopper or magazine to its normal position. Various adjustments are provided for in the construction just described. Thus the hopper or magazine may be raised or lowered, to dispose its lower end at the proper height with reference to the path of the carrier, by shifting the upper part of the two-part stand 14^e vertically upon the lower part thereof, suitable slots being provided in connection with the bolts 14^a, 14^b, Fig. 6, which hold the two parts in fixed connection. The hopper or magazine may be shifted transversely, either by shifting the supporting-rod 14^c endwise through socket 14^d, or by shifting the collar 14^g, hub 14^b, and hopper or magazine along the said supporting-rod. The inclination of the hopper or magazine when in a state of rest may be varied by angular adjustment of hub 14^a and its arm 14^m around the supporting-rod.

To provide a place of attachment or holder for the free ends of the weft or filling threads which are carried by the weft-carriers 15 in the hopper or magazine, a pin 21 projects outward from the latter and has applied to its outer end a hub 21^a, upon which the said ends are wrapped by the weaver, the portions leading from the weft-carriers to the said hub being led rearward and caught in a fork 22^a in an arm 22 projecting from hub 21^a rearward in line with the outer end of the lay, and a little above the level of the shuttle-box. The said fork is employed in order to aid in causing the weft or filling of a weft-carrier which has just been introduced into a shuttle on the lay to enter the self-threading delivery-eye of such shuttle as the latter makes its first flight toward the opposite side of the loom. This fork holds the weft end in such position that as the shuttle makes its first flight, the portion of yarn or thread extending from the weft-carrier that has just been placed in the shuttle to the fork finds its way naturally into the self-threading eye.

The means for feeding the weft-carriers that are contained in the hopper or magazine one at a time to the carrier 16 is on the escapement order. It is shown in Figs. 1, 3, and 5 to 8. A small rockshaft 23 is mounted in bearings in the ears 14^b, 14^b, on the front of the hopper or magazine. This rockshaft has fixedly mounted thereon

two depending arms 23^a, 23^b, provided at their lower end with rearwardly facing detents. By means of a contracting spiral spring 24, which is engaged with a rearwardly-projecting lug upon the inner end 70 of the rockshaft 23, these detents are caused to project rearwardly into the interior of the hopper or magazine into position to receive thereon the head and tip, respectively, of the lowermost weft-carrier in the hopper 75 or magazine. They thus support the said weft-carrier and also the others above the same. When forward movement of the carrier 16 carries it toward position to receive a weft-carrier, a pin 25 mounted on the carrier engages a projection 25^a from arm 23^a, and rocks the rockshaft 23 to swing both detents forward so as to release the lowermost weft-carrier and permit it to enter the carrier 16, which at that instant presents its 80 receiving portions in line with the delivery-portions of the side-guides of the hopper or magazine. The other weft-carriers are prevented from passing down, by means of a presser-finger 26 that is fixed upon a rockshaft 27 mounted in a bearing at the rear of the hopper or magazine. When the detents are withdrawn forwardly, the presser-finger is drawn forward against the exterior 85 of the yarn-mass upon the next to the lowermost weft-carrier, by means of a contracting spiral spring 28 extending from an arm 23^c fixed on rockshaft 23 to an arm 27^c fixed on rockshaft 27. When the carrier 16 moves 90 rearward, taking with it the weft-carrier 100 it has just received from the hopper or magazine, the spring 24 acts to rock the rockshaft 23 reversely to swing the detents into position again, and in this rocking movement of the said rockshaft its arm 23^c acts 105 against arm 27^c to rock the rockshaft 27 so as to remove the presser 26 from engagement with the weft-carrier which is now the lowermost. Thereupon the weft-carriers drop until the lowermost one comes to rest 110 upon the detents.

A shelf 29, Figs. 1, 3, and 6, projects rearwardly from the hopper or magazine below the position occupied by the carrier 16 when it receives a weft-carrier, so as to prevent the latter from passing through the carrier 16. The carrier 16 is provided with opposite side-pieces spaced apart sufficiently to receive between them the length of a weft-carrier, as in Figs. 6 and 7, 115 and having inwardly facing lips 161, 161, as in Figs. 5, 7, and 8, for engagement with the head and tip of a weft-carrier at the rear of the latter. Flat springs, 162, 162, are attached by their forward ends to lugs 120 projecting inwardly from the said side-pieces. The rear portions of the said springs incline downward and rearward toward the lips 161, 161. The latter curve forward 125 and downward. A weft-carrier descending 130

from the hopper or magazine into the carrier rests between the lips 161, 161, and the downwardly and rearwardly inclined rear portions of the springs. Should the weight 5 of the superincumbent weft-carriers in the hopper or magazine tend to carry the lowermost weft-carrier entirely through the carrier 16, such weft-carrier will be arrested within the carrier by the shelf 29 of the hopper or magazine. The springs will hold 10 the weft-carrier from dropping after the carrier 16 has been moved rearward away from the shelf. When the carrier 16 has presented the weft-carrier in position to enter the shuttle, the springs will yield to permit pressure applied by the transferrer to push the weft-carrier from the carrier 16 into the shuttle.

For the support and actuation of the carrier 16 it is mounted upon the upper end of an arm 163, Figs. 1 and 2, which latter is mounted at its lower end upon a pivot 164 carried by the loom-frame. Such arm carries a roll 165, Fig. 3, which is held pressed 25 against a cam 166 on change-shaft 210 by means of a contracting spiral spring 167, Fig. 1. To insure proper register of the carrier 16 with the interior of the hopper and with that of the shuttle on the lay, a

30 guide-piece 168, Figs. 1 and 3, is fixed upon the loom-frame, the said guide-piece having a slot which is occupied by the arm 163. The walls of said slot confine the arm laterally, and guide it in its movements.

35 In the rearward movement of the carrier that is produced by spring 167 when the latter is permitted to move the carrier, it passes above the front-plate 7 of the shuttle-box on the adjacent end of the lay, at 40 a height slightly above that of a shuttle occupying such shuttle-box, until the weft-carrier which it holds is presented in position to properly enter such shuttle. An adjustable stop-screw 169 carried by the cross-bar 16^a of the carrier serves by its contact with some part of the lay to arrest the carrier in the proper position with relation to the shuttle.

45 For the purpose of moving the chute 18 from the forwardly-retracted position occupied by it in Fig. 1 to a working position beneath the shuttle-box, so that it may receive the weft-carrier expelled from the shuttle, when such weft-carrier drops, and deflect it into the receiving-box 19, and of afterward restoring the chute to its position in Fig. 1, the chute is affixed to a bracket 181 which in turn is mounted upon arm 163, as shown in Figs. 1 and 3.

60 The transferrer 17, by which the weft-carrier is transferred from carrier 16 to the shuttle in the shuttle-box of the lay at the replenishing ~~rate~~ of the loom, is substantially like transmitters heretofore employed in looms of the same general class, but is

fixed upon a rockshaft 171 (Figs. 1, 9, 10 and 11) mounted in three bearings, one thereof provided in an arm 172 forming part of the top-plate 10 of the shuttle-box, one in a stand 172^a bolted to the said top-plate as shown in Figs. 10 and 11, and one in a stand 172^a bolted to the back of the lay-beam, said arm and stands projecting at the back of the lay. Hence, the transferrer is carried by the lay and moves forward and back in unison therewith. The transferrer is operatively combined with the change-shaft 210 by means of a rod 173, lever 174, and cam 175 on the change-shaft, the said lever being held in contact with the said cam by the action of a contracting spiral spring 176. By the action of the said cam the transferrer is depressed after the carrier has taken position above the shuttle in the shuttle-box, so as to push the weft-carrier from the carrier into the shuttle, the entering weft-carrier expelling the one previously contained in the shuttle, as usual. The spring 176 raises the transferrer to its idle position again.

90 The shuttle-positioning arm 20 (Figs. 9, 10 and 11) has a slot 201 therein to receive the shuttle-tip. The said arm is fixed upon the forward end of a rockshaft 202, extending from front to rear and mounted in bearings 95 upon the stand 172^a bolted as aforesaid upon the top-plate 10. For the actuation of the shuttle-positioning arm 20, an arm 204 is mounted upon the rear end of rockshaft 202. Such arm is joined by a connecting-rod 205 to a lever 206 that is held in engagement with a cam 207 on change-shaft 210 by means of a contracting spiral spring 208. In order to enable the shuttle-positioning arm 20 to yield in its positioning movement, in case it descends upon a misplaced shuttle, and thereby avoid breakage of parts and injury to the shuttle, the arm 204 is loose upon rockshaft 202 and is connected by a contracting spiral spring 209 with an arm 20^a that is fixed upon the said rockshaft. By the tension of the spring, stops 20^b and 20^c with which the arms 204 and 20^a are provided are held in contact with each other. When cam 207 produces 115 movement of arm 204 the spring 209 causes arm 20^a, rockshaft 202, and the shuttle-positioning arm 20, to move in unison with arm 204, and the shuttle-positioning arm is thereby caused to act to position a shuttle occupying the shuttle-box. Should the shuttle-positioning arm descend upon the shuttle the spring 209 will yield, allowing the shuttle-positioning arm to be arrested while arm 204 completes its movement.

120 During the regular operation of the loom the parts concerned in making change of weft-carriers remain in the positions represented in the drawings, with the carrier 16 holding a weft-carrier and occupying an in- 130

termmediate position between the hopper or magazine and the lay. When the change is called and the change-shaft begins to rotate, the carrier 16 is moved rearward until it 5 meets the lay, taking a position above the shuttle-box and presenting the weft-carrier between the shuttle and the transerrer. The chute 18, moving rearward in unison with the carrier 16, takes a position under 10 the opening in the lay through which the expelled weft-carrier will presently pass. The shuttle-positioner having been actuated to position the shuttle in the shuttle-box, the transerrer is caused to act, transferring 15 the fresh weft-carrier from carrier 16 to the shuttle and expelling the previous weft-carrier from the shuttle, the expelled weft-carrier falling upon the chute and being deflected thereby into the receptacle 19. The 20 shuttle-positioning arm and transerrer rise to normal position, and the carrier 16 and chute move forward. The forward movement carries the carrier 16 far enough to cause its pin 25 to operate the detents of 25 the hopper or magazine to release the lower-most weft-carrier, such weft carrier dropping into the carrier, while presser 26 is caused to bear against the next succeeding weft-carrier to prevent the same from dropping. The carrier moves rearward to its 30 intermediate position shown in Fig. 1. This releases the detents, which swing rearward into working position and at the same time the presser 26 is moved to release the weft- 35 carrier held thereby, such weft-carrier dropping upon the detents. The operations thus having been completed, the change-shaft ceases its rotation and the change mechanism comes to rest.

40 The means for actuating the change-shaft 210, and the means for calling the said shaft into action, may vary. Figs. 2, 4, 13, 14 and 15 show devices and arrangements for the said purposes. In these figures, 30 45 is a worm-gear mounted loosely upon the change-shaft 210 and kept in continuous rotation by means of a worm 31 in engagement therewith, such worm being fixed upon the lower end of an inclined shaft 32 carrying at its upper end a bevel pinion 33 meshing with a bevel gear-wheel 34 fixed to and rotating with a continuously driven band-pulley 35 loose upon the crank-shaft 5. A clutch-device for clutching the said worm-gear 30 to the change-shaft when it is 50 required to rotate the latter comprises a lever 36 which is pivoted at 361, Figs. 13 and 15, to the hub of a disk 371 fixed on the change-shaft 210, the said lever being adapted to 55 swing in a plane extending longitudinally of the change-shaft, and being provided upon one arm thereof with a tooth 37 working through a hole in the said disk 371 and adapted to enter the respective holes of the 60 circular series of holes 38 formed in the said

worm-gear 30. Said clutch lever 36 is acted upon by a contracting spiral spring 39, which is bent over one arm of the said lever and has its opposite ends connected with one side of the disk, the said spring 70 tending to press the tooth 37 toward the worm-gear. An arm of the clutch lever diametrically opposite from that carrying the tooth 37 is adapted to engage with a cam-shaped portion of a controlling-arm 40, the 75 latter being pivoted at 41 upon a fixed stand 42, and hanging downward from its pivot. The controlling-arm 40 has pivoted thereto at 43, Figs. 4 and 14, a latch 44 working through a slotted fixed guide 45, 80 the said latch having connected therewith a contracting spiral spring 46, Figs. 4 and 14, acting with a tendency to draw the latch and the controlling-arm 40 toward the 85 wheels 371 and 30, and also to draw the 90 latch downward. Normally, the parts occupy positions that are indicated in Figs. 4, 14, and 15, namely, with the shoulder of the latch 44 in engagement with the bottom of the slot in the guide 45, and with the 95 tail-end of the clutch-lever 36 in contact with the lateral prominence of the controlling-arm 40, so that the clutch-tooth 37 is drawn out of engagement with the wheel 30, and the said wheel 30 revolves without 100 transmitting rotation to the change-shaft 21. Figs. 2, and 4 show ordinary weft-fork mechanism, which is represented as in operative control of the driving connections of the change-shaft which have just been described. Thus, a weft-fork is shown at 47, 48 being the weft-fork slide, 49 being a dog connected with the said slide and adapted to engage with the upper end of an arm 50 mounted on a rockshaft 51, the latter in 105 turn being mounted at the front of the breast-beam 2, and having a rearwardly and downwardly extending arm 52 from which a wire 53 extends to the latch 44. The weft-hammer is shown at 54, Fig. 2, and at 110 55 is the actuating cam therefor, the said cam being mounted upon the cam-shaft 56, the latter being driven from the crank-shaft 5 in usual manner by means of the gear wheels 57 and 58, Figs. 2 and 4. When the 115 weft fails, and in consequence the weft-fork 47 is not tilted, so that the weft-hammer engages with the tail of the weft-fork and moves the weft-fork slide 48 forward, this forward movement of slide 48 causes the 120 dog 49 to engage with the arm 50, and as a result the rockshaft 51 is rocked, and the arm 52 draws upward the wire 53, thereby lifting the latch 44 out of engagement with the bottom of the slot in the guide 45, thereby permitting arm 40 to yield to the pressure transmitted to the same from the spring 39 through the clutch lever 36, so that the tooth 37 of the said clutch lever is 125 allowed to enter the next one of the holes 130

38 which is presented opposite the same in the rotation of the worm-gear 30. This 5 clutches the worm-gear 30 to the change-shaft 210, and the change-shaft begins its rotation. As soon as the rotation of the change-shaft carries the toe of the clutch lever 36 away from the prominence of the cam-shaped portion of the arm 40, the spring 46 acts to move the said arm 40 toward the wheels 371 and 30, and the shoulder of the latch 44 drops into engagement with the bottom of the slotted guide 45 again, so that as the change-shaft completes a rotation the tail-end of the clutch lever 10 36 again encounters the cam-shaped portion of the controller-arm 40, and the clutch lever is thereby operated to disengage its tooth 37 from the worm-gear 30. The change-shaft thereupon comes to rest.

15 The various cams upon the change-shaft are as heretofore contrived to cause the various operations which are incident to a change of weft-carriers to be performed during one rotation of the said shaft. The 20 change-shaft is shown provided with the restarting cam 60, Fig. 1, by means of which, on the conclusion of the change-operations, the weaving instrumentalities are restarted automatically through the restarting lever 25 61, which is held in contact with the said cam by the contracting spiral spring 176, and the rod 62 bearing a collar 63 against which the said restarting lever acts, the said rod connecting with an arm 64 on the shipping rockshaft 65 substantially as in Letters 30 Patent No. 945,722 aforesaid. As in the said Letters Patent, the weft-fork mechanism is connected to occasion a suspension of the working of the weaving instrumentalities 35 for the change operations at the same time that the change-shaft is called into operation. Thus, the rockshaft 51 is shown provided in Fig. 2 with a toe 70 adapted for engagement with a shoulder 71 of the ship- 40 per-handle 72, the latter being fixed upon one end of the shipping rockshaft 65. The result of such engagement is to throw the shipper-handle over rearward. This shifts past center the pin 73 connecting to the shipper-handle the upper end of the link 74 connecting with the bell-crank 75 controlling the driving-clutch of the loom-mechanism, the path of the pin 73 being such as to allow link 74 to move downward. Consequently the spring 76 connected to the 45 brake-lever 77 carrying the pin 78 which extends over the horizontal arm of said bell-crank is permitted to draw down the brake-lever and said horizontal arm, and simultaneously unclutch the loom-mechanism from band-pulley 35 and apply the brake 79 to bring the weaving instrumentalities to a state of rest. When the restarting cam 60 acts to turn the shipping rockshaft 65 re- 50 versely, so as to carry shipper-handle 72 forward, the return movement of pin 73 moves link 74 upward and pulls upward the clutch-operating bell-crank 75 and brake-lever 77, thereby releasing the brake and clutching the weaving instrumentalities to the band-pulley so as to restart the loom.

55 A feature of considerable practical importance is the safety-lock for the change-mechanism. This prevents the change-mechanism from being tripped into action, accidentally or otherwise, while the loom-shipper 72 is "on" and the loom continues uninterrupted its regular weaving operations. It also prevents the change-shaft from accidentally becoming clutched to the continuously rotating worm-gear 30 while the loom is standing still during an ordinary stoppage of the loom, with the shipper thrown. The said safety-lock is shown at 60 Figs. 2, 4, 13, 14, 15. It comprises a member that is pivoted at 81 to the lower portion of the fixed guide 45 for the latch 44. The said portion of the said guide is slotted at 45^a for the pivotal mounting of the safety-lock member, to permit of vertical shift of the pivot and the said member to provide for proper engagement of the hooks of the safety-lock with the top of the latch. The safety-lock member is constructed with upwardly extending arms 80^a and 80^b between which the latch plays up and down, the said arms being formed with shoulders or hooks, each of which is adapted to fit over the top of the latch so as to hold the latter from rising. The two hooks face 65 each other and are separated by an intervening space through which the latch may pass upward above the hooks or descend between them. Swinging movement of the safety-lock member in one direction carries one of the hooks away from the latch and the other into position to engage with the latch to hold it from rising, and movement of said member in the reverse direction carries the latter hook away from the position for 70 engagement with the latch and the other hook into position for such engagement. Thus the hooks are arranged for alternate engagement. A contracting spiral spring 82, that is engaged with a rearwardly-projecting lug on the safety-lock tends to hold the safety-lock in its normal position represented in Figs. 13, 14, 15, with its rear hook in engagement with the top of the latch. The safety-lock is moved into its opposite 75 position through connections with the loom-shipper 72 comprising a wire 83 and the link 74. The said wire has its lower end connected to a forwardly-projecting lug on the safety-lock, the upper portion of said wire extending up through a hole in a projection 84, Fig. 2, on the lower end of link 74, and receiving thereon above the said projection a collar 85 that is fastened in place by a clamp-screw. When the loom-shipper is 80

85 90 95 100 105 110 115 120 125 130

thrown, as when the loom is stopped, as in Fig. 2, the projection 84 of link 74 is sufficiently below collar 85 to leave the safety-lock free to the action of its spring 82, which accordingly holds the safety-lock in the position shown, namely with its rear hook over the top of the latch. Consequently the latch cannot be raised by the action of the weft-fork mechanism if the latter is manipulated by hand, or in case the loom is turned over by hand, and it cannot become lifted or thrown up by any accident. Therefore, the change mechanism cannot be started into operation so long as 10 the loom-shipper remains thrown. When the loom-shipper is moved to start the loom, the rise of link 74 as pin 73 passes upward and forward causes projection 84 of the said link to engage collar 85 and move wire 83 upward, turning the safety-lock member so as to swing its rear hook out of engagement with the top of the latch and its front hook into engagement therewith. Consequently, 20 so long as the loom-shipper remains "on", and the loom continues in regular operation, the latch cannot be lifted or thrown up either accidentally or by intention.

The only time when the latch can move upward is during the middle portion of 30 the movement of the safety-lock in either direction. The parts are so set and adjusted that when the weft-fork mechanism acts to throw the loom-shipper and swing upward the arm 52 to lift the latch 44, the space between the hooks of the safety-lock is presented above the said latch at just the right time to permit the automatic lifting of the latch. The latch drops back into its lowered position during the return 40 swing of the safety-lock member as the loom-shipper is restored to "on" position. 21^a, Figs. 1 and 5, is a plate that is supported at the outer side of the hopper or magazine and projects rearwardly beyond the same. This plate has an inclined rear edge against which the weft-ends extending from the weft-carriers in the hopper or magazine to the fork 22^a rest, and by which they are partly supported as the weft-carriers descend into the lower portion of the hopper or magazine. The said inclined rear edge guides the weft-ends rearward as they slide down the same in the descent of the weft-carriers, and takes up some of the slack 50 therein. Extending downward from the lower rear corner of plate 21^a is a curved extension 21^b, which prevents the said weft-ends from being brushed forward by the carrier 16 as it moves forward into the position to receive a fresh weft-carrier from the hopper or magazine.

The shuttle-positioning devices have been made the subject of claim in my divisional application filed August 9, 1918, Serial No. 65 783,857.

What is claimed as the invention is:—

1. In a loom, the combination with the lay, a hopper or magazine for weft-carriers, and means for transferring the weft-carriers successively to a shuttle on the lay, of a 73 detent for the lowermost weft-carrier in the hopper or magazine, operated by a member of the transferring means to deliver said weft-carrier to said means, a presser which clamps and detains the next weft-carrier when said delivery takes place, and means for alternating the detent and presser in their operation.

2. In a loom, the combination with the lay, a hopper or magazine for weft-carriers, 80 and means for transferring the weft-carriers successively to a shuttle on the lay, of a detent for the lowermost weft-carrier in the hopper or magazine, operated by a member of the transferring means to deliver 85 said weft-carrier to said means, a presser, a spring by which the presser is caused to clamp and detain the next weft-carrier when said delivery takes place, and means whereby as said detent closes into working 90 position it operates the presser to release the weft-carrier that is detained thereby.

3. In a loom, the combination with the lay, a hopper or magazine for weft-carriers, 95 and means for transferring the weft-carriers successively to a shuttle on the lay, of a detent for the lowermost weft-carrier in the hopper or magazine, operated by a member of the transferring means to deliver said weft-carrier to said means, a presser, 100 a spring operatively connecting said detent and said presser and acting in the withdrawal of the detent to cause said presser to clamp and detain the next succeeding weft-carrier, and means through which the 105 returning movement of the detent opens said presser away from the latter weft-carrier to release it.

4. In a loom, in combination, a hopper or magazine for weft-carriers, means for 110 transferring said weft-carriers successively, a rocker, a detent in connection therewith, a spring actuating said rocker to cause said detent to detain the lowermost weft-carrier in the hopper or magazine, a second rocker, 115 a presser in connection therewith, means for transmitting movement from the first rocker to the second to retract the presser as the detent is advanced into working position, and a spring returning the presser to clamp 120 the next higher weft-carrier as the detent is withdrawn to deliver the lowermost weft-carrier to the transferring means.

5. In a loom, in combination, a lay, a 125 magazine for weft-carriers, an open-topped carrier, means for loading a weft-carrier from said magazine into said carrier by movement vertically, means for moving said carrier to present the said weft-carrier into position to enter a shuttle on the lay, and 130

means for transferring the weft-carrier from the carrier to the shuttle.

6. In a loom, in combination, a lay, a magazine for weft-carriers, a carrier which is supplied with a weft-carrier from said magazine, means for moving said carrier to present said weft-carrier in position above a shuttle on the lay, means in connection with the carrier and the lay for securing

10 proper register of the weft-carrier held by the carrier with the opening of the shuttle, so that said weft-carrier shall be enabled to enter said opening properly, and a trans- ferrer which inserts said weft-carrier into such shuttle.

7. In a loom, in combination, a lay, a magazine for weft-carriers, a carrier which is supplied with a weft-carrier from said magazine, means for moving said carrier to

20 present said weft-carrier in position to enter a shuttle on the lay, means in connection with the carrier and the lay for securing

proper register of the weft-carrier held by the carrier with the opening of the shuttle,

25 so that said weft-carrier shall be enabled to enter said opening properly, and a trans- ferrer which inserts said weft-carrier into such shuttle.

8. In a loom, in combination, a lay, a magazine for weft-carriers, a carrier which is supplied with a weft-carrier from said magazine, a transerrer which inserts such

30 weft-carrier into a shuttle on the lay, and a change-shaft in operative control of said carrier and transerrer and serving through its rotation to effectuate the operation of the same.

9. In a loom, in combination, a lay, a magazine for weft-carriers, a carrier which is supplied with a weft-carrier from said

40 magazine, a transerrer mounted on the lay for inserting such weft-carrier into a shuttle on the lay, and a change-shaft in operative control of said carrier and transerrer and

45 serving through its rotation to effectuate the operation of the same.

10. In a loom, in combination, a lay, a weft-carrier carrier having a normal position forward, and movable rearward to- 50 ward the lay, and a chute for an expelled weft-carrier operatively combined with said carrier and given its working position to receive the expelled weft-carrier by the movement of the carrier toward the lay.

55 11. In a loom, in combination, a lay, a change-shaft, a weft-carrier carrier oper- atively controlled by the change-shaft, and a chute operatively combined with said car- rier and moving simultaneously therewith.

60 12. In a loom, in combination, a lay, a magazine for weft-carriers, a carrier which is supplied with a weft-carrier from said magazine, a transerrer mounted on the lay, and a change-shaft operatively combined 65 with said carrier and actuating the latter

to meet the lay and present its weft-carrier in position to be transferred to a shuttle on the lay, and also operatively combined with said transerrer whereby the latter is actuated to transfer the weft-carrier from the 70 carrier to the shuttle.

13. In a loom, in combination, a lay, a weft-carrier magazine, a carrier which is supplied with a weft-carrier from said mag- 75 azine, a swinging supporting-arm for the said carrier, a chute connected with said arm, and means for operating the said arm to move the carrier and chute simultane- ously toward the lay.

14. In a loom, in combination, a lay, a 80 weft-carrier magazine, a carrier which is supplied with a weft-carrier from said mag- azine, a swinging supporting-arm for said carrier, a chute connected with said arm, and a change-shaft operatively combined 85 with said arm.

15. In a loom, in combination, a change- 90 shaft, a change-shaft drive, a loom-shipper, devices for tripping the loom-shipper and also tripping said drive into action to operate the change-shaft, and a lock operatively controlled by said loom-shipper preventing establishment of driving relations at an im- proper time.

16. In a loom, in combination, a change- 95 shaft, a change-shaft drive including a clutch and clutch-controlling means, a loom- shipper, devices by which the loom-shipper is tripped, and by which also said clutch is tripped to establish driving relations be- 100 tween said drive and the change-shaft, and a lock for said clutch-controlling means, itself operatively controlled by said loom- shipper, preventing establishment of such relations at an improper time. 105

17. In a loom, in combination, a lay, a magazine for weft-carriers, a carrier which is supplied with a weft-carrier from said magazine, means to move said carrier to present the said weft-carrier into position 110 to enter a shuttle on the lay, means for transferring the weft-carrier from the car- rier to the shuttle, and means for suspending the operation of the weaving instrumen- talities for the performance of the change- 115 operations and subsequently automatically causing such instrumentalities to resume op- eration.

18. In a loom, in combination, a lay, a magazine for weft-carriers, a carrier which 120 is supplied with a weft-carrier from said magazine, means for moving said carrier to present said weft-carrier in position above a shuttle on the lay, a transerrer which in- serts said weft-carrier into such shuttle, and 125 means for suspending the operation of the weaving instrumentalities for the perform- ance of the change-operations and subse- quently automatically causing such instru- mentalities to resume operation. 130

19. In a loom, in combination, a lay, a magazine for weft-carriers, a carrier which is supplied with a weft-carrier from said magazine, means for moving said carrier to present said weft-carrier in position to enter a shuttle on the lay, a transerrer mounted on the lay which inserts said weft-carrier into such shuttle, and means for suspending the operation of the weaving instrumentalities for the performance of the change-operations and subsequently automatically causing such instrumentalities to resume operation.
20. In a loom, in combination, a lay, a magazine for weft-carriers, a carrier which is supplied with a weft-carrier from said magazine, a transerrer which inserts such weft-carrier into a shuttle on the lay, a change-shaft in operative control of said carrier and transerrer but inoperative during the regular working of the loom, and means for calling the change-shaft into operation and suspending the operation of the weaving instrumentalities for the performance of the change-operations and subsequently causing such instrumentalities to resume operation and the change-shaft to become inoperative.
21. In a loom, in combination, a lay, a magazine for weft-carriers, a carrier which is supplied with a weft-carrier from said magazine, a transerrer mounted on the lay for inserting such weft-carrier into a shuttle
- on the lay, a change-shaft in operative control of the said carrier and transerrer, and means for calling the change-shaft into operation and suspending the operation of the weaving instrumentalities for the performance of the change-operations and subsequently causing such instrumentalities to resume operation and the change-shaft to become inoperative.
22. In a loom, in combination, a lay, a magazine for weft-carriers, a carrier which is supplied with a weft-carrier from said magazine, a transerrer mounted on the lay, a change-shaft operatively combined with said carrier and controlling the latter to meet the lay and present its weft-carrier in position to be transferred to a shuttle on the lay, and also operatively combined with said transerrer and controlling the latter to transfer the weft-carrier from the carrier to the shuttle, and means for calling the change-shaft into operation and suspending the operation of the weaving instrumentalities for the performance of the change-operations and subsequently causing such instrumentalities to resume operation and the change-shaft to become inoperative.

In testimony whereof I affix my signature in presence of two witnesses.

SIMEON S. JACKSON.
